UNITED STATES PATENT OFFICE

ORA S. JACKSON, OF OMAHA, NEBRASKA, ASSIGNOR TO GENERAL STEEL CASTINGS CORPORATION, OF GRANITE CITY, ILLINOIS, A CORPORATION OF DELAWARE

LOCOMOTIVE STRUCTURE

Application filed November 14, 1929. Serial No. 407,198.

My invention relates to railway rolling stock and consists in a novel construction of a locomotive air reservoir and associated structure. I direct attention to my copending application Serial No. 407,198, filed November 14, 1929.

The general object of my invention, like that of the above mentioned application, is to produce a locomotive air reservoir located between the side frames of the locomotive and formed of sufficient cross sectional area to serve as a reinforcement of the frames and also forming a longitudinal member of the framing adapted to transmit longitudinal forces.

A more specific object of my invention is to simplify the casting operation of a reservoir member which is cast integral with the underframe. I also desire, in the preferred form of my invention, to form a section of a reservoir reinforcement member which, in part, is integral with the locomotive bed or frame and to complete the member with a separately formed section applied thereto. In the preferred form of my invention the side frames of the locomotive are united by a cylindrical reservoir member which either by itself, or in combination with co-operating members applied thereto, forms the "backbone" of the frame and serves to transmit the major portion of the vertical and longitudinal forces present in the frame.

These and other detailed objects of my invention are attained by the structure illustrated in the accompanying drawings in which—

Figure 1 is a top view of one-half of a locomotive frame embodying my invention.

Figure 2 is a side elevation of the same.

Figure 3 is a vertical longitudinal section through the center of the reservoir and associated structure taken on line 3—3 of Figure 1.

Figure 4 is a vertical cross section through the structure, the left hand portion of Figure 4 being taken on the line 4—4 of Figure 2 and the right hand portion of Figure 4 being taken on the line 4^a—4^a of Figure 2.

Figure 5 is a vertical cross section, the left hand portion being taken on the line 5—5 of

Figure 2 and the right hand portion being taken on the line 5^a—5^a of Figure 2.

Figure 6 is a detail vertical longitudinal section illustrating a slight modification.

Figure 7 is a top view of a longitudinal half of the modified construction.

Figure 8 is a side elevation of the same.

Figure 9 is a transverse section, the left hand portion being taken on the line 9—9 of Figure 8 and the right hand portion being taken on the line 9^a—9^a of Figure 8.

Figures 10 and 11 are, respectively, top and side views illustrating another modification of my invention.

Figure 12 is a top view of one longitudinal half of another form of my invention.

Figure 13 is a side elevation of the same.

Figure 14 is a vertical transverse section, the left hand portion being taken on the line 14—14 of Figure 13 and the right hand portion being taken on the line 14^a—14^a of Figure 13.

Figure 15 is a detail vertical longitudinal section of the structure shown in Figure 12.

Figure 16 is a similar detail section illustrating a modification.

Figure 17 is a vertical transverse section through one-half of a modified structure.

Figure 18 is a similar section illustrating another modification.

Figure 19 is a similar section illustrating another modification.

Figure 20 is a similar section illustrating another modification.

In the construction illustrated in Figures 1 to 5, inclusive, the side frames are indicated at 1 and are shown as including pedestal jaws 2 and provided at intervals with equalizer fulcrums 3 and brake hanger brackets 4. The frames are united at their rear by a transverse member 6 which also forms the front end of a cradle having sides 7. While I show this cradle structure as formed integrally with frames 1, it will be understood that it may be separately formed and attached to the frames. The forward ends of the frames merge to form the front deck 8 and this portion of the structure is provided with integral pads 9 for mounting the brake cylinder 10.

- Intermediate the side frames 1 and extending throughout a substantial portion of the length of the structure is a cylindrical member 11 having open ends and connected to the side frames by vertically spaced substantially horizontal webs 12 which are provided with substantial openings 13, whereby the structure is lightened.
- Preferably, member 11, webs 12 and side frames 1 are all formed integrally with each other, either by casting in a single unit or by the welding together into an autogenous whole parts which have been formed separately. The structure is reinforced by upstanding ribs 14 and by shorter upstanding elements 15 which also form brackets for mounting piping for conducting air, water and other fluids from one part of the locomotive to another. Below member 11 and merging therewith and with the pedestal jaws 2 are cross members or transoms 16. Suitable integral brackets 5 are provided at intervals for mounting the expansion plates 17 on which the boiler shell 18 is carried.
- Member 11 terminates at its ends in vertical flanges 19 and the end portions of the reservoir are formed by cup-shaped members 20 and 21, respectively, each having flanges 22 on its inner end adapted to be bolted to the corresponding flanges 19 of the central member 11 of the reservoir. Horizontal flanges 23 are provided on the outer ends of members 20 and 21 and rest on the transverse members 6 and 8 of the frame.
- In order that the members 20 and 21 may serve as reinforcements of the frame structure, I provide complementary lugs 25 and 26 on the frame and flange respectively and utilize wedges 27 to provide a thrust-resisting engagement between the lugs on the two parts. With this construction variations in the length and machining of members 11, 20 and 21 may be accommodated and draft and buffing forces may be absorbed or transmitted by the reservoir structure, the same forming a "backbone" of cylindrical section throughout that portion of the locomotive frame in which the effective depth of the side frames is greatly reduced because of the recesses for the driver axle boxes.
- The side frames 1 are braced by suitable transoms or cross bars 28 extending below reservoir members 20 and 21 and having their upper elements depressed, as best shown in Figure 5, to clear the reservoir. End members 20 and 21 are provided with piping brackets 29 corresponding to brackets 15 on the central member 11.
- In Figure 6 I indicate a modified form of wedging the reservoir end member 30 to the frame member 31. In this construction, a single wedge or key 32 is provided between lugs 33 and 34.
- Figures 7, 8 and 9 illustrate a modification

in which a cylindrical reservoir body member 35 is provided with integral brackets 36 for attachment to locomotive side frame members 37, and reservoir end members 38 are provided with similar brackets 39 for attachment to the side frames. Members 35 and 38 have abutting flanges 40 for attachment to each other and each of these members is preferably provided with brackets 41 for mounting piping. Members 38 also have expansion plate brackets 42 and member 35 has depending elements forming a transom 43 having a flange 44 for connection to the pedestal jaw 37a. With the above described structure, smaller units may be used and secured together by bolts, rivets or welding and, at the same time, the bracing of the side frame by cylindrical reinforcing member is effected.

Figures 10 and 11 illustrate another modification of the structure shown in Figures 1 to 5 in that the end members 45 applied to the open-ended cylindrical body 46 are relatively short and, in effect, comprise caps for the central member and have no connection with the side frames 47, apart from their connection to the body member 46. With this construction, a relatively short reservoir is provided but the hollow cylindrical reinforcement of the spaced side frames is retained.

If desired, the frames may be connected to each other in any usual manner at points spaced from the reservoir longitudinally of the frame.

Figures 12 to 15 illustrate a construction in which the reservoir main body member 48 comprises a cylinder with flanged ends 49 to which caps 50 are applied. Caps 50 include lateral extensions 51 secured to the side frames 52, preferably including expansion plate brackets 54 and brake hanger lugs 55 and piping brackets 56.

A transom 53 may be located intermediate the ends of the reservoir for the purpose of bracing the side frames but member 53 has no connection with the reservoir member 48 and does not extend over the top of the same.

Figure 16 illustrates a modified form of connection between the main reservoir member 57 and the end members 58. The latter is provided with a rib 59 spaced from its inner surface 60 and providing a shouldered recess adapted to receive the edge and adjacent portion of the cylindrical body member 57. Member 58 is welded to 57 at W.

In the construction illustrated in Figure 13, the reservoir is so located relative to the pedestals that the end members 50 are intermediate the drivers and there is no occasion for providing members 51 with the downward extensions for connection to the pedestal jaws such as are provided on member 53 but it will be understood that if the length of the reservoir is such as to bring the end members abreast of pedestal jaws, it would

be an obvious advantage to provide the end members with such downward extensions.

Figure 17 illustrates a modification of the intermediate bars 61 for the side frames in which the same is shown as extending around the reservoir 62 which is made separately and placed in the mold before the cross tie is poured.

In the construction shown in Figure 18, the transverse bars 63 are formed integrally with the side frames 64 and extend around the reservoir 65 which is made separately and placed in the mold before pouring the frame.

Figure 19 illustrates a structure similar to that shown in Figure 17 but in which the upper portion 66 of the transverse bars 67 is formed separately from the lower and main portion and is bolted or riveted thereto as indicated at 68.

Figure 20 illustrates a similar modification of the structure shown in Figure 18, the lower main portion 68 of the transverse bars being formed integrally with the side frame 69, the upper portion 70 being formed separately 25 and secured to the lower portion and frame by bolts or rivets at 71.

In each of the forms of my invention described above, the side frames are braced by a tubular member which also forms an air reservoir located between the frames. This construction avoids the location of reservoirs on the exterior of the boiler shell and eliminates the material and labor required for securing the reservoirs in their usual location. The center of gravity of the locomotive is lowered and less material is required for the side frames in order to attain a given resistance to forces transmitted through the underframe.

Various other modifications in the details and arrangement of the reservoir parts may be made without departing from the spirit of my invention and I contemplate the exclusive use of such variations as come within the scope of my claims.

I claim:

1. In a locomotive underframe structure, spaced side frames, and an open end cylinder extending longitudinally of and between said frames and rigid therewith and forming part of an air reservoir.

2. A one-piece casting comprising locomotive side frames, with driver box pedestals, and an open end cylindrical member merging with said side frames and forming a reinforcement for the same and also forming the main body portion of an air reservoir.

3. A one-piece casting comprising a locomotive underframe with side members of box-shape cross section having pedestal jaws depending therefrom, and an open end cylindrical reservoir-forming member intermediate and parallel with said side members, there being transverse horizontally disposed webs extending from the upper and lower walls of

said side members to the corresponding portions of said cylindrical member.

4. In a locomotive frame, a central longitudinally extending cylinder with transverse flanges projecting outwardly therefrom, side members integral with said flanges, pedestal jaws integral with said side members, and cup-like members applied to the ends of and closing the said cylinder, said cylinder and members cooperating to form a main longitudinal force-transmitting part of the frame.

5. In a locomotive frame, a central longitudinally extending cylinder with radial flanges at its ends, side members extending longitudinally of the frame beyond the ends of said cylinder, and cup-like members having radial flanges secured to said cylinder flanges, said cup-like members forming a continuation of and closing the ends of said cylinder.

6. In a locomotive frame, side frames, a cradle element and a front deck element bracing said side frames, and an open end cylinder forming part of an air reservoir and extending longitudinally of the frame and terminating at points spaced from said elements and bracing said side frames between said elements.

7. In a locomotive bed casting, side frames with driver box pedestals, a front deck, brake cylinder mounting elements on said deck, brake hanger brackets, an intermediate longitudinally disposed open end cylinder, and air pipe brackets on said cylinder, all formed integrally.

8. In a locomotive bed casting, side frames with driver box pedestals, a front deck, brake cylinder mounting elements on said deck, brake hanger brackets, an intermediate longitudinally disposed open end cylinder, air pipe brackets on said cylinder, all formed integrally, and separately formed longitudinally extending cup-like members fitting the ends of said cylinder and closing the same and secured thereto and to said frames to cooperate with the latter in transmitting longitudinal forces through the locomotive.

9. In a locomotive frame, side members, and a centrally located compressed air tank comprising a plurality of sections secured together end to end, at least one of said sections being integral with said side members to brace the latter transversely of the frame.

10. In a locomotive frame, side members, and a centrally located compressed air tank comprising a plurality of sections secured together end to end, and a plurality of transoms spaced longitudinally of said side members and connecting the same to each other and to at least one of said sections.

11. In a locomotive, side frames, an open end cylinder extending longitudinally of and between said frames, transoms connecting said cylinder and side frames, cup-like members secured to the ends of said cylinder, and

- transoms between said frames and extending under said cup-like members.
12. In a locomotive, side frames, an open end cylinder extending longitudinally of and between said frames and united therewith, a transverse member spaced from the end of said cylinder and connecting said frames, and a cup-like member with its open end applied to said cylinder and with its closed end resting on said transverse member.
13. In a locomotive, side frames, an open end cylinder extending longitudinally of and between said frames and united therewith, a transverse member spaced from the end of said cylinder and connecting said frames, a cup-like member with its open end applied to said cylinder and with its closed end resting on said transverse member, and interengaging elements on said members for transferring longitudinal forces between them.
14. In a locomotive underframe, side frames, an open end cylinder extending longitudinally of and between said frames and united therewith, a transverse member spaced from the end of said cylinder and connecting said frames and united therewith, a cup-like member with its open end applied to said cylinder and with its closed end resting on said transverse member, and means for transferring longitudinal forces between said members comprising opposed lugs on said members and a wedge element between said lugs.
15. In a locomotive underframe, side frames, an open end cylinder extending longitudinally of and between said frames and united therewith, transverse members spaced from the end of said cylinder and connecting said frames and united therewith, cup-like members with their open ends applied to said cylinder and with their closed ends resting on said transverse members, respectively, and means for transferring longitudinal forces between said members comprising opposed lugs on said members and wedge elements between said lugs.
16. In a locomotive underframe, side frames, and a cylindrical reservoir comprising a series of sections arranged longitudinally of and between said side frames and connected thereto, there being expansion plate brackets on said sections for mounting the locomotive boiler shell.
17. In a locomotive underframe, side frames, and a cylindrical reservoir comprising a series of sections arranged longitudinally of and between said side frames and connected thereto, there being brackets on said sections for carrying piping above said reservoir.
18. In a locomotive underframe, side frames, a cylindrical reservoir comprising a series of sections arranged longitudinally of and between said side frames and connected thereto, and a brake hanger lug on one of said sections.
19. In a locomotive frame, side members, and a centrally located compressed air tank comprising a plurality of sections secured together end to end, at least one of said sections being integral with said side members.
20. In a locomotive frame, side members, and an air reservoir comprising a plurality of cylindrical sections forming a part of the frame.
21. In a locomotive frame, side members, cross members, and an air reservoir comprising a plurality of separately formed sections, said members and one of said sections comprising an integral structure, another of said sections being secured to said first mentioned section and to said structure.
22. In a locomotive bed casting, side frames with driver box pedestals, a front deck, brake cylinder mounting elements on said deck, brake hanger brackets, and an intermediate longitudinally disposed open end cylinder, all formed integrally.
23. In a locomotive bed casting, side frames with driver box pedestals, a front deck, brake cylinder mounting elements on said deck, brake hanger brackets, an intermediate longitudinally disposed open end cylinder, all formed integrally, and separately formed longitudinally extending cup-like members fitting the ends of said cylinder and closing the same and secured thereto and to said frames to cooperate with the latter in transmitting longitudinal forces through the locomotive.
24. In a locomotive, side frames, an air tank located between said side frames and comprising a plurality of separately formed sections, a transom rigidly connecting said side frames and at least one section of said tank, and another transom rigidly connecting said side frames but spaced from and extending under another of said sections.
25. In a locomotive frame, side members, and a centrally located tank comprising a plurality of sections secured to each other, at least one of said sections being integral with said side members to brace the latter transversely of the frame.
26. In a locomotive frame, side members, cross members, an air reservoir located between said side members and comprising a main section and at least one separately formed closure section, said members and main section being formed integrally.
- In testimony whereof I hereunto affix my signature this 8th day of November, 1929.
- ORA S. JACKSON.
